LIQUID SPRAYER

William H. Rose, Jersey City, N. J., assignor to
Stanco Incorporated

Application June 21, 1940, Serial No. 341,686

12 Claims. (Cl. 299—89)

The present invention relates to a method and means for spraying or atomizing liquids, and particularly to a means for spraying liquid insecticides and like materials.

It is an object of the invention to provide a method and means for producing an insecticide spray in which a major portion of the liquid particles will be so finely divided as to remain suspended in the air for a considerable period of time. It is also an object to provide an atomizing device in which with only slight changes, the quality of the discharge may be varied from a light to a heavy concentration of liquid in air. A further object is to provide a reservoir spray gun, in which provision is made for the operative combination of a spray gun pump with a conventional form of shipping container for the liquid.

This invention and its objects may be fully understood from the following specification when it is read in conjunction with the accompanying drawings, in which:

Fig. 1 is a vertical section longitudinally of a spray pump and reservoir of the character contemplated;

Fig. 2 is a similar view through a portion of an alternate arrangement;

Figs. 3 to 6A, inclusive, are end views of discharge heads showing suitable discharge opening patterns;

Figs. 7 and 8 are vertical sections through alternate types of discharge head fillers;

Figs. 9 to 13, inclusive, are vertical sectional views through alternate forms of discharge head assemblies; and

Fig. 14 is a vertical section through a valved discharge head.

In describing the invention as illustrated by the drawings, like parts have been designated by the same numerals.

Referring to Fig. 1, the numeral 1 designates a reservoir for fluid, which is preferably a small size can in which the fluid is sold, having a threaded nozzle or pouring spout 2, and thereby provided for engagement in fluid-tight relation with a spray pump barrel 3 by means of the cap member 4, soldered or otherwise secured to the barrel. A fluid feed tube 5, carried at the forward end of the barrel 3, and opening therein, extends downward through and beyond the cap 4 for such distance as to bring it into closely spaced relation with the bottom of the container to be used. The tube is provided with a balance opening 6 at a point normally above the liquid within the container, and should be maintained in fluid-

tight relation with both the cap and the pump barrel at their points of contact. A fluid-tight seal also must be maintained between the cap 4 and nozzle 2, as by gasket 7.

5 The spray pump is of generally conventional nature, having a pump plunger 8 disposed in the barrel 3, except that the spray discharge head is formed according to the inventive concept herein set forth.

10 A partition 9, having an air passage opening 9a, disposed adjacent the end of the barrel, forms a chamber 10 in communication with the reservoir 1 by way of the tube 5. The partition 9 also serves to prevent any free liquid which may be present in the chamber 10, from time to time, from draining back into the pump barrel. The closure 11 for the end of the barrel is provided with an opening or openings 12 to permit the discharge of a fluid spray. In the form shown by Fig. 1, a disc 13 of an absorbent and preferably a non-fibrous material, such as fine cellulose sponge, a porous ceramic material, pumice, or fine steel wool, and the like.

The material used is preferably one having a 20 multitude of small, generally discontinuous cells, voids or passages distributed in closely adjacent relation throughout the mass of the material, the mass of the material, however, being of such nature as to be substantially self-supporting. As 25 indicative of the characteristics of the material contemplated, it may be said that the preferred material is one in which:

1. The number of cells, voids or passages is not substantially less than 45,000 per cubic inch;
2. The total air space produced by the voids, cells or passages is equivalent to approximately 97% of the volume per cubic inch;
3. The average size of the cells, voids or passages does not substantially exceed .034 inch.

40 Of the materials suitable for use as indicated above, that which is most preferred is a fine cellulose sponge material, which may be produced under such controlled conditions as to obtain the characteristics desired.

45 Although a self-supporting filler material is preferred for use, various structural devices may also be utilized to maintain not only the original conformation of the disc, but also its relative position in the assembly. In the arrangement according to Fig. 1, the partition 9 is provided with a flange portion 9b which, in cooperation with the closure 11, maintains the disc 13 in proper operating relationship in the assembly.

50 The structure illustrated in Fig. 1, while a simple embodiment of the invention, may be re-

ferred to in describing the principles and methods of operation. The principle of operation differs from that of comparable apparatus now known in the art, in that in a simple structure, the conventional siphon tube for lifting fluid from the reservoir has been dispensed with, in favor of an arrangement which provides for positive, pressure lifting or displacement of liquid from the reservoir. Whereas, in the conventional spray pump, the fluid is lifted and sprayed on the forward stroke of the pump plunger, in the apparatus according to this invention, a two step operation is contemplated.

On the forward stroke of the plunger 8, air is forced through the opening 9a into chamber 10. The absorbent filler disc 13, while permitting the passage of air to discharge through the closure 11 by way of openings 12, in combination with the closure 11, restricts the flow of air to such an extent that a slight excess of pressure is built up in the chamber 10. The chamber 10 being in substantially free communication with the reservoir through tube 5, the pressure in the chamber and in the reservoir tend to equalize, at a point slightly above atmospheric. On the rearward stroke of the plunger 8, the pressure in the chamber 10 and the pump barrel is slightly reduced, creating a pressure differential between the reservoir and the chamber 10 which forces a portion of the fluid contents from the reservoir into the chamber, where it is absorbed by the material of the disc 13. It is to be specifically noted that this is not the conventional siphon action. On the next forward stroke of the plunger 8, the liquid is sprayed from the discharge openings 12, while the pressure within the reservoir is renewed. At the same time, any free liquid in the chamber 10 is forced back into the reservoir. The diameter of the tube 5 must be proportioned substantially with relation to the pump barrel 3 and with the absorbent capacity and air resistance of the absorbent filler 13. If the tube is too large, or the absorbent filler of too great density, an excess amount of air will be forced into the reservoir, and may cause flooding of the chamber 10 on the next rearward stroke of the plunger. The balance which must be obtained is not extremely critical, however, and may be readily determined by simple experimentation in any particular instance, or may be calculated by conventional methods. The principal function of the balance opening 6 is to prevent an accumulation of pressure in the reservoir when not in active use. This opening is not of sufficient size, however, to interfere with the operation of the sprayer in the manner set forth above.

Before the initial use of the device, or when it has remained idle for a considerable period of time, its operation is facilitated if the absorbent filler element is first well wet with liquid. This can be done most simply by partially or entirely blocking the discharge port in the head 11, while building up a slight pressure in the liquid reservoir. Upon releasing such pressure by removing the port obstruction, the spray liquid will tend to flood the chamber 10 sufficiently to thoroughly wet the filler element. If the filler is not pre-wetted, its resistance to the passage of air, when dry, may not be sufficient to build up an intermittent pressure in the reservoir which will be high enough to raise a column of liquid through the conduit means 5. When using a discharge head which is removable as later described, the filler may be wetted before the head is applied.

In Fig. 2 the inventive concept is shown applied in a slightly different manner. In the apparatus illustrated, the pump or sprayer barrel 3 is adapted for attachment to a reservoir in which the tube 5 is carried by the nozzle member 2. Also as shown, the partition is spaced from the filler disc 13, and a retainer member 12a is utilized to maintain the position of the disc. It should be noted that in the construction shown, the joints between the pump barrel 3 and cap member 4 should be fluid-tight, and also that the cap 3 should be adapted to make a fluid-tight connection with the nozzle 2. One way in which this may be accomplished is illustrated. A disc 2a of an air pervious substantially absorbent material, such as felt or the like, being inserted between the nozzle closure and tube supporting element 2b, and the inner face of the cap. To some extent, this disc 2a modifies the pressuring effect on the reservoir, and tends to produce a drier but higher velocity spray, due to an increase in the pressure and amount of air discharged through the absorbent disc 13.

As may be apparent, the means by which the pump barrel 3 is affixed to the reservoir nozzle 2 is variable within wide limits, but other arrangements which are particularly suited for use in this invention, have been disclosed in a co-pending application Serial No. 311,380, filed December 30, 1939.

With reference to the Figs. 3, 4, 5, and 6, it will be noted that contrary to conventional practice when using a siphon tube sprayer, a variety of spray opening patterns are made possible, whereby the utility of the spray device is enlarged. If desired, the opening shown in Fig. 5 may be centered and also it may be enlarged within such limits as are determined by the size of the sprayer and the result desired. With a large single opening, it is usually desirable to insert a piece of wire or fabric mesh between the closure member 11 and the disc 13 in order to avoid distortion or bulging of a spongy, absorbent material under pressure from within the barrel, or to assist in the spray dispersion.

Referring particularly to Fig. 6 and the related sectional view 6A, a variable spray head has been illustrated in which a closure member 11, having an enlarged opening of the type shown in Fig. 5, is backed by a rotatable disc 11a having a variety of discharge opening patterns 12a punched therein. The disc 11a may be supported as by a loosely applied rivet 11b, which being firmly affixed to the disc 11a extends through the closure 11 and terminates exteriorly in a winged end by means of which the disc 11a may be turned so as to bring any desired spray pattern into register with the fixed opening 12 in closure member 11.

In addition to the possibility of varying the form of the spray discharge by the use of different discharge patterns as illustrated in Figs. 4 to 6 inclusive, it is also possible to vary the character of the discharge by means of changes in the nature or form of the absorbent filler element 13. As shown in Figs. 7 and 8, a disc 13 of any of the materials mentioned may be partially or completely perforated as at 13a, the perforations to coincide with the discharge openings in the particular discharge head or closure which may be used. Many variations and combinations are also possible in the form of the disc arrangement. For example, the disc shown in Fig. 8, may be of half the illustrated thickness, and backed by a similar or greater thickness of the

same or an equivalent material to produce a disc member having the same or similar characteristics to those of the disc member shown in Fig. 7. It is to be noted that although a considerable variety of materials are available for use in forming the disc members contemplated, it is preferred to use a material which is substantially unaffected physically by either oily or aqueous materials. Of these materials, artificial sponge made from cellulose is preferred, as it is easy to cut and shape, and perforations such as have been described in connection with Figs. 7 and 8 may be made easily and will not be substantially changed by use.

More elaborate arrangements for the construction of the spray discharge head are illustrated in Figs. 9 to 13 inclusive, but all are within the scope of the concept set forth in the description of Figs. 1 and 2. The principal object of the variations may be said to be for the purpose of obtaining refinements of construction or operation.

In Figs. 9, 9a, 9b, and 9c, there has been illustrated a form of the device in which provision has been made for the most efficient distribution of fluid from the reservoir and of air from the pump barrel and discharge head chamber. As shown, the structure comprises a pump barrel 3 having an end closure 11, in which are disposed horizontally arranged discharge opening 12, more clearly illustrated by Fig. 9a. The end closure 11 with the annular partition 9 forms a discharge head chamber of greater length and capacity than shown in any of the previously illustrated structures. The chamber furthermore is not in free communication with the reservoir through the tube 5 as in Fig. 1, the principle of modifying the pressuring effect on the reservoir as mentioned with respect to the arrangement shown in Fig. 2 having been developed further. In this modification, an annular anti-flooding member 14 is disposed in the rearward portion of the chamber against the partition 9, covering the upper end of the tube 5. (Fig. 9c provides an end view of the member 14.) Thus, as previously mentioned, pressure to the reservoir on the forward stroke of the piston, is modified to some extent, as is the flow of liquid from the reservoir on the rearward stroke. In addition, the member 14 acts as a reservoir for any excess of liquid which may rise into the chamber, permitting the liquid to be more gradually absorbed by the filler 13. This member 14 is preferably separated from the disc or absorbent filler member 13 by means of spacer disc 15 which may be conveniently formed from thin metal or from tough paper and the like. The spacer disc 15 also serves as an air distribution medium, in that within the area of the opening in the annular member 14, the disc is provided with perforations 15a, as shown in the Figure 9b, to provide a plurality of air streams through the filler 13, and thus prevent localized drying of the filler by a single stream of air. In addition, peripheral cuts 15b in the disc 15, provide for easier transfer of liquid from the annular member or from the tube 5.

In Fig. 10, a modification is illustrated in which the absorbent filler 13, and the annular member designated as 14 in Fig. 9, are combined in a single member 16. In this showing, the member 16 is of generally tubular nature, closed at the end abutting against the pump barrel closure 11, and open at the end adjoining the piston 8 or partition 9. The member 16 is of such length

that it covers and extends beyond the edge portions of the cap member 4, which, in this embodiment, is set into a side-wall of the pump barrel in order to obtain a more compact sprayer assembly. Although shown as adapted for use with a reservoir of the type illustrated in Fig. 2, obviously, the cap member may also be provided with a tube 5 in the fashion shown in Fig. 1. Another feature illustrated in this embodiment is the use of a removable closure element 11, which, as shown, is provided for threaded engagement with the end of the barrel 3, thereby providing for interchangeability of closure elements having different discharge opening patterns. In the present instance, openings are provided in the closure 11 to correspond with the passages provided through the closed end of element 16 in the manner described and illustrated by Figs. 7 and 8.

In Fig. 11, a structural arrangement is illustrated which provides one means to accomplish production line assembly of such sprayers. As shown, the absorbent filler 13 is first packed in a cylindrical, two part container or discharge head 17, comprising a spray discharge portion 17a and an air distributing portion 17b. The two parts are joined in fluid-tight relation and then soldered or otherwise joined to the end of a pump barrel 3, in which the partition 9 previously has been inserted.

If desired, provision may be made for the threaded attachment of the head 17 to the barrel 3 for the same purposes as mentioned in connection with Fig. 10, and further, for the purpose of permitting the use of one sprayer barrel or pump in spraying either oily or aqueous liquids, which obviously may not be sprayed through the same filler element once it has been used in either service. When assembled in such fashion, the discharge heads may be fabricated separately and brought together with a prefabricated pump barrel at any convenient assembly point. Also, when using cellulose sponge with aqueous materials, it is desirable that the sponge be completely enclosed, as shown, in order to prevent swelling when wet.

To substantially overcome any tendency of the nebulized particles of liquid to unite as droplets at the discharge openings, and collecting there, to run out and drop from the discharge head, Figs. 12 and 13 illustrate a form of construction in which a liquid collection area is provided directly behind the discharge head closure 11. As shown, the absorbent filler element 13 is spaced from the closure 11 either by means of an annular stop 18, as in Fig. 12, or by a perforate partition 19 as in Fig. 13. In the arrangement according to Fig. 12, nebulization is a sole function of the absorbent material carried on within the head, with only a portion of the total spray being discharged through the opening 12 in the head. In the arrangement according to Fig. 13, however, the partition 19 is provided with perforations 19a which function in the same fashion as those illustrated, for example, in Fig. 3, and the closure 11 is provided with an enlarged opening 12 through which the inner portions of the spray stream is discharged. In both forms however, those portions of the spray stream which may unite to form droplets tend to collect in the area provided, and run back into the absorbent material. In the structure according to Fig. 13, the partition 19 is provided with an opening 19b, or a series of such openings, similar to the cuts shown as 15b in the disc 15 illus-

trated by Fig. 9b. These cuts permit the filler element 13 to re-absorb any liquid which may not be discharged in nebulized form, or which may drip from around the openings in the partition 19.

Fig. 14 illustrates the application of a means for controlling the flow of liquid to an absorbent material in the discharge head of a device such as illustrated in Fig. 1. As shown, a gland member 20 is secured to the upper surface of the head portion of the sprayer barrel 3, directly over the tube 5. A needle valve member 21 having a knurled top, is provided for threaded engagement in the gland member, and may be turned down or up to regulate the flow of liquid from the tube 5, and also the air delivered through said tube. A lock nut 22 maintains the setting of the needle valve as desired.

As has been indicated, the invention is not limited to any specific embodiment set forth for the purpose of illustration, and various changes may be made in the apparatus as described within the scope of the invention as set forth by the appended claims.

I claim:

1. A sprayer device comprising in combination with a reservoir for liquid, a spray discharge assembly above and in pressure-tight relation to the reservoir, including a ported discharge head, a conduit for liquid opening at one end into the head, and at the other end into a body of liquid confined in said reservoir, a means for producing surges of pressure air through said head, and a means for restricting the flow of pressure air through the head, diverting a portion of the pressure air through said conduit into the liquid reservoir, said means including a liquid-absorbent, fluid-dispersing element, adapted to receive liquid through said conduit, between surges, under pressure of the air diverted to said reservoir.

2. A sprayer according to claim 1, in which the liquid-absorbent, fluid-dispersing element is a disc of a cellular, non-fibrous material disposed laterally of the head, forward of the conduit opening therein.

3. A sprayer according to claim 1, in which the liquid-absorbent, fluid-dispersing element is a packing of a non-fibrous material substantially filling the head and covering the conduit opening therein.

4. A sprayer according to claim 1, in which the liquid-absorbent, fluid-dispersing element is a substantially cylindrical member, closed at one end, disposed in the head with the closed end of the cylinder adjacent the outer ported end thereof, and a side wall portion covering the conduit opening into the head.

5. In a sprayer of the character described, a discharge head assembly, comprising a casing, a conduit for liquid opening into the casing at an

intermediate point thereof, a closure for one end of the casing having a discharge port therein, a liquid-absorbent, fluid-dispersing element in said head between the discharge port and conduit opening, and a valve means carried by the casing to alter the effective area of the conduit opening in said casing.

6. A sprayer, comprising a spray pump barrel having a discharge end, means carried by the barrel adjacent the discharge end to engage a reservoir for liquid, a ported discharge end closure for said barrel and a perforate, lateral partition disposed within the barrel in spaced relation to said closure member, a conduit carried by the spray barrel, opening thereinto, forward of the partition and extending downward through the reservoir engaging means, and a liquid-absorbent, fluid-dispersing filler element in said barrel, interposed between the discharge port and said conduit, said filler element adapted to divert a portion of the pressure air deliverable through said barrel into the conduit tube, and receiving liquid therethrough from a reservoir, when attached.

7. In a sprayer according to claim 6 in which the filler element comprises a body of a non-fibrous, liquid-absorbent material, the mass of said material substantially enclosing a multitude of cells, voids or air passages, of which the greater number are separated one from another by liquid permeable walls of the material.

8. In a sprayer according to claim 6 in which the filler element comprises a body of non-fibrous, liquid-absorbent material having a substantially cellular structure, in which the total volume of cells, voids and air passages is equal to about 97% of the volume of the body of material.

9. In a sprayer according to claim 6 in which the filler element comprises a body of a non-fibrous, liquid-absorbent material having a substantially cellular structure, in which the total number of cells, voids and air passages is substantially 45,000 per cubic inch of the material.

10. In a sprayer according to claim 6 in which the filler element comprises a body of a non-fibrous, liquid-absorbent material, the mass of said material substantially enclosing a multitude of cells, voids or air passages of which the greater number are separated one from the other by liquid permeable walls of the material, said cells, voids or air passages each having an average size not substantially exceeding .034 inch.

11. In a sprayer according to claim 6 in which the filler element comprises a body of a non-fibrous liquid absorbent material and passages are provided in the material.

12. A sprayer according to claim 6 in which the filler element is spaced from the end closure to form a liquid collection area behind the closure.
